UNITED STATES PATENT OFFICE.

CHARLES FRANCIS JENKINS, OF WASHINGTON, DISTRICT OF COLUMBIA.

AEROPLANE.

1,383,465.

Specification of Letters Patent.

Patented July 5, 1921.

Application filed July 9, 1919. Serial No. 309,722.

To all whom it may concern:

Be it known that I, CHARLES FRANCIS JENKINS, a citizen of the United States, and resident of Washington, in the District of Columbia, have invented certain new and useful Improvements in Aeroplanes, of which the following is a specification, reference being had therein to the accompanying drawing.

In aviation it is usual, in landing, to check the momentum of the machine by turning the machine upward thereby increasing the expenditure of machine - advancing energy upon the body of air in front, but there are well known disadvantages in this method, which requires skill and quick action. The objects of this invention are to destroy the machine's momentum quickly but without causing sudden deviation in the path of the machine, and at the same time to make special skill and quickness of far less importance. These ends are attained by arranging the upper main plane to have its upward inclination quickly increased without correspondingly changing the inclination of the lower main plane, and at the same time automatically changing correspondingly the inclination of the horizontal rear elevating and depressing plane, whereby the lower main plane is aided in resisting sudden upward movement of the machine.

In the accompanying drawings,

Figure 1 is a view showing a machine embodying my invention.

Fig. 2 is a front detail view.

Figs. 3 and 4 are detail views looking in the direction of the arrows at 3-3, 4-4, Fig. 2.

Fig. 5 is a partial front view of a modified construction.

Figs. 6, 7 and 8 are enlarged detail views of devices of Fig. 5.

Figs. 9, 10 are details of lock and control devices.

Figs. 11, 12 illustrate a second modification.

In these figures, A represents a common body of an aeroplane, B, B' the main planes and C the tail-vane, all normally having the

usual relative positions. Between the planes are forward struts D and rear struts D' connected by diagonal tension wires E.

The angle made by the lower plane with the struts is, as usual, unchangeable, but the upper plane is pivoted at F to the upper end of the rear struts to swing in a vertical plane and its forward side is secured to the upper ends of the forward struts by links G, G' allowing it to be thrown up to a limited distance. The links G are virtually crank-like arms non-revolubly mounted upon a shaft H rocking in bearings in the upper ends of the struts D, the shaft being in this instance shown as square and held in disks I revoluble in the struts D. Each link G normally extends downwardly and at its lower end is pivoted the lower end of one of the links G' the upper end of which is pivoted to the upper plane or the forward side of its framework. The link G' is curved and the axis of its lower pivot normally lies, as seen in Fig. 1, a little to the right of the axis of the shaft H so that it is locked, any upward strain exerted by the link tending to throw the arm or crank G against any suitable stop or stops J. Near the aviator's seat, a depending hand lever K, like the usual quadrant lever, is revolubly mounted on the shaft H, and alongside it is a short arm L non-revolubly mounted upon the shaft and having in its end a notch M to receive the end of a quadrant lever pawl N which is pressed into the notch by the common spring. When the upper plane is to have its upward inclination increased, the pawl is retracted so that it can pass over that part of the arm on one side of the notch, but not far enough to pass over the part on the other side. The hand lever being now pushed forward, the pawl presses the longer portion of the arm L and carries it forward out of locking position when the upward pressure of the air upon the plane swings the plane upward about its rear pivots until the two links are extended as indicated in dotted lines in Fig. 1, the lever, if desired, still being held in the hand with its pawl retracted below the path of the shorter side of the arm L. As the link thus swings it

pulls a wire O which rocks the horizontal tail vane so that it tends to lift this part of the machine and keep the machine nearly level in fore and aft direction. Naturally, 5 the greatly increased angle of the upper plane gives much greater resistance to advance and absorbs the momentum of the machine, and at the same time the normally inclined lower plane offers great resistance to 10 sudden rising of the forward end of the machine. The result is that speed of advance is greatly reduced, that the machine immediately begins to fall, and as it is kept level, the great wings act much like a large 15 parachute as the machine gently descends to earth. When it comes fully to rest, gravity swings the front side of the upper plane to initial position, and if the pawl be retracted momentarily it reengages the arm L.

20 Obviously, changes may be made while preserving the broad invention. For example, the mounting and connections of the shaft H may be changed, or the arm L may be extended to form a hand lever which may be released, pushed over to swing the link G out of locked position, and then allowed to swing with the rocking shaft H. Some such modifications are shown in Figs. 5, 6, 7, 8, 9, 10, 11, 12, which also add some desirable 25 features. In these figures 13, 14 represent upper and lower planes, and 15, 16 front and rear struts connected by common wire stays 17. The rear side of the upper plane is pivoted at 18 to the upper end of the rear 30 struts 16, while the front side of the same plane is connected to the front struts by motor-operated devices which allow the swinging of the plane by rapid yet gradual movement. A small motor 19, Fig. 5, is shown 35 as carried by the upper plane, and, by usual worm gearing 20, rotating a drum 21 on a shaft 22. Pulleys 23, 24 are fixed to each strut and to the upper plane just above the strut, and from the drum a cable 25, having adjusting turn-buckles 25', passes 40 around each pair of pulleys to form there- with a small "block and tackle" which, when the motor runs in the proper direction, draws the plane down upon the struts, or, 45 when the motor runs in the opposite direction, allows the forward side of the plane to swing from its struts under the strong air pressure due to the machine's advance. On some or all the struts 15 a perforated lug 50 26 extends upward, when the upper plane rests upon the strut, between coacting lugs 27, and a cotter pin 28 is passed through the three securely holding the plane down. These pins may be connected to the cable 55 25 (Fig. 9) in such way that slight rotation of the motor withdraws them. A closed liquid-filled cylinder 29, Fig. 10, may be secured to one or more of the struts and provided with a piston 30 carried by the plane above, 60 a by-pass 31 extending from the upper part

of the cylinder to the lower part so that the fluid may flow around the piston allowing movement in either direction. A valve 32 controls the by-pass and in effect locks the plane in any position. These locking and 70 controlling devices are usable with all the forms herein set forth.

Instead of the drums and cables, I may employ an extension 33 of the motor shaft (Fig. 11) and provide it at intervals with 75 worms 34 to engage worm gears 35, each lying between lugs 36 borne by the upper plane, and splined to a threaded vertical shaft 37 working in said lugs and, by oppositely inclined threads, in a nut fixed to the 80 corresponding strut. Obviously rotation of the motor carries the plane to and from the struts and holds it securely at any point where the motor may allow it to remain.

What I claim is:

1. The combination with a suitable aeroplane body, of a main supporting plane connected to the body extending equally on each side thereof and arranged to swing upwardly as a whole about an axis near its 90 own rear side, a tail vane arranged to swing similarly in unison with the plane, and means whereby an operator may prevent and permit such swinging.

2. A biplane having one of its supporting main planes fixed to the fuselage or body and the other of its main supporting planes pivoted near its rear side to swing upward as a whole through a positively limited angle, combined with means normally locking 100 the pivoted plane positively against swinging, and operator controlled devices for rendering the locking means ineffective.

3. The combination with a suitable aeroplane body and relatively fixed main plane, 105 of a second main plane arranged to swing upwardly, as a whole, about an axis near its rear side to increase the surface resisting forward movement in the air, and means for automatically limiting the rate of the swing- 110 ing permitted.

4. The combination with a biplane having its body, struts, tail vanes, and main supporting planes in usual relative positions but with one of the planes arranged to swing 115 as a whole upwardly about an axis near its rear side, of positively locking devices normally making swinging of the plane im- 120 possible, operator controlled means for temporarily rendering the locking devices in- effective, and means whereby swinging of the plane is automatically limited to a pre- determined rate.

5. The combination with an aeroplane body having a relatively fixed main support- 125 ing plane and fixed upwardly extending struts, of a second main supporting plane hinged to the rear line of struts to swing upwardly, devices for locking the forward side of the hinged plane to the forward line 130

of struts, and operator controlled devices for rendering the locking devices operative or inoperative at will.

6. The combination with an aeroplane body of a main supporting plane arranged for swinging upwardly under air pressure about an axis near its rear side, means for locking the plane against such swinging

whatever the air pressure, means for releasing the locking means, means for limiting to a small angle the swinging of the released plane, and means for automatically limiting the rate of swinging movement.

In testimony whereof I hereunto affix my signature.

CHARLES FRANCIS JENKINS.
